UNITED STATES PATENT OFFICE

FERRUCCIO TRINCHERO, OF GENOA, ITALY, ASSIGNOR TO ENRICO GARDA, OF TURIN, ITALY

CONTROLLING MEANS FOR ELECTRIC LIGHTING INSTALLATION OF RAILWAY CARS

Application filed February 6, 1928. Serial No. 252,343.

This invention relates to a device for controlling electric lighting installations particularly adapted for use in connection with railway cars that repeatedly pass from day-
5 light zones to zones where artificial lighting is necessary.

This invention is applicable to either direct or alternating current installations and comprises a main circuit for the lamps, a
10 circuit shunted thereto including a selenium cell or a similar device with variable conductivity according to the intensity of light. An electro-magnet which operates an interrupter in the light circuit is con-
15 trolled by two relays which are energized according to the resistance of the selenium cell and a variable resistance in a second shunt circuit. The attraction of the elec-
20 tro-magnet for lighting or extinguishing the lamps being effected by the different intensity of the current in the circuits.

In carrying out the object of the invention generally stated above, it will be understood, of course, that the essential features
25 thereof are susceptible to changes in details and structural arrangements, one preferred and practical embodiment being shown in the accompanying drawings, wherein:

Fig. 1 is a diagrammatical view, and Fig.
30 2 an end view showing the arrangement of the relays and circuit interrupters. Fig. 3 is an enlarged fragmentary front view.

Referring to the drawings, in the main circuit are inserted the lamps L with a
35 switch A controlled by the movement of a soft iron armature operated by a group of two relays forming the arrangement B. The current flowing in the two relays is dis-
tributed by means of the special switch C.

40 In the circuit 1—4—5 of the relay 14 there is inserted a resistance R capable of being regulated in proportion to the value of the ohmic resistance of the selenium cell S inserted in the circuit 1—4—6—7 of relay
45 13, when said cell, which may be called "the sensitive eye of the apparatus" is nearly in the dark.

In the main circuit, before inserting the apparatus subject matter of the invention,
50 there may be inserted a common switch to

insulate the apparatus from the line and allow the lighting of the lamps by means of usual switches.

In the drawings it is to be assumed the selenium cell S is in the dark and the lamps 55 lighted according to the adjustment of the resistance R inserted in the circuit 1—4—5 and the current flowing therein is of a higher intensity than that flowing through the cell S. When this occurs the relay 14 at-
60 tracts the armature 19 to the position as shown in dotted lines, which action causes the pawl 15 of the insulating disc of the armature to make contact with the spring plate 16 on the insulating bearing member I 65 whereupon the circuit through 10—3—15—
16—11—20—17'—8—5-relay 14 is closed. The resistance R at this time is inactive and the contacts 20 and 17' are in engagement
70 with each other before the snapping of the switch C, and the cell S is still illuminated. The current now flows through the main circuit and to the relay 14 suddenly drawing with force the armature, thus causing the same to assume the position as shown 75 in full lines.

At the same instant the tooth 22 of the disc of the armature strikes against the wing 23 of the switch or circuit breaker C, whereupon the wing recoils while the other 80 wing 25 pushes the small column 24 into the position shown in the drawings. The column 24 is held in place by the spiral spring 33 fixed to the pivot of the column, which carries the contact plates 20—21 in-
85 sulated from one another, whereupon the contact 21 engages the contact 17 and the current is through 10—3—15—16—11—20—
17'—8—5 and relay 14 is broken and allows the circuit 1—4—5 with the resistance R 90 included to be free again, so that the armature 19 may return in due time to its first position, illustrated in dotted lines and in the meantime always keeping the pawl 15 in contact with spring plate 16. Said ar-
95 rangement allows the apparatus,—while making the contact for lighting the lamps,— to be in condition to break the said contact as soon as the cell is acted upon by the sun-
light; and when it is sufficiently illuminated 100

then a larger current flows in the circuit 1—4—6—7, the relay 13 thus drawing the magnet 19, which by means of pawl 15 and plate 18 closes the circuit 10—3—15—18—5 12—21—17—9—6—4—1 the cell being at the same time excluded.

The relay 13 is at that moment traversed by a current of a high intensity, the armature 19 being thus suddenly drawn and 10 brought in the opposite position illustrated in the drawings by a continuous line.

This movement at the same moment causes the tooth 22 to strike against the wing 25 of the switch C with the contemporaneous displacement of column 24 by means of wing 23 and making the contact 20—17, the circuit 10—3—15—18—12—21—17—9—6—4—1 being consequently broken and the cell being isolated.

20 The movement of the switch in reverse directions is limited by the pins 23' which may be suitably supported and are arranged in the path of movement of the wing 23.

The interrupter A is a knife switch and 25 is operated by a pawl 26 placed on the disc of the armature in a position symmetrical to that of pawl 15. The pawl 26, following the movement of the armature, acts between the arms of a rod 28 pivoting in a bearing member 27 united to wire 10. The rod 28 is connected through a coil spring 30 to the knife bearing rod 29 of the interrupter pivoting in the same support 27. The coil spring 30 under suitable tension allows the 35 knife to be secured in the positions it has been pushed to.

The two stops 31 and 32 with adjustable screw control the amplitude of the movement of rod 29.

40 The apparatus is provided with only two magnets, no auxiliary magnets existing with intermediary controlling or connecting functions.

The apparatus works in both cases of a 45 direct or alternate current, no current rectifier being necessary.

The movement of attraction of the magnet for lighting or extinguishing the lamps with the corresponding breaking of the circuits is caused by the different intensity of the current in the circuits no antagonistic springs being consequently required, a ready controlling effect and a safe stability in both the positions of the magnet being at the 55 same time secured.

The switch owing to the characteristics of the arrangements described allows the use of direct or alternate current indifferently.

60 A current of high intensity is flowing in the controlling circuits, relays and cell only in the moment on which switch and interrupter snap.

Both springs 16 and 18 are not antagonistic, but simple laminated springs securing

and keeping the contact in both movements of the armature from the beginning of its attraction to its subsequent violent approaching to the magnet of the relay.

70 Sparking in the points of contact of the pawl of the armature's disc with both plates is avoided, the passage of said pawl from one to the other of its positions being very rapid and secure.

The effect of the light may be modified 75 at will so that the functioning of the installation may be anticipated or delayed.

The selenium cell is protected by a special calotte shaped glass screen arranged on insulating socket on which the cell is fixed, the 80 conducting wires terminating also thereon. All these elements together form an important part of the installation and may be called the "sensitive eye", being normally arranged on a vertical plane to be better 85 exposed to the different conditions of light. On the upper part of the glass calotte a special cover may be adapted even extending over the median line of the calotte, this cover being suitably made transparent or 90 ground or colored in order that a powerful light, directly incident upon the cell owing to the generation of a strong current will not cause a rapid deterioration of the cell. The "sensitive eye" gives, on the contrary, 95 a diffused light uniformly distributed.

What I claim as new and desire to secure by Letters Patent is:

An electric lighting installation especially adapted for lighting railway cars including 100 a main circuit, a shunt circuit connected with the main circuit and including a selenium cell and an electro-magnet, a second circuit connected in shunt with the main circuit and including a second electro-magnet 105 and a variable resistance, a circuit interrupter in said main circuit, an armature associated with said interrupter and actuated by said magnets to effect the opening and closing of said main circuit, means for cutting out said resistance temporarily in said 110 second named shunt circuit in response to a current in said second named shunt circuit larger than the current in said first named shunt circuit and means for cutting out said 115 selenium cell temporarily in said first named circuit in response to a current in said first named shunt circuit larger than the current in said second named shunt circuit whereby said main circuit may be opened and closed 120 according to any variation of intensity of light.

In testimony whereof I affix my signature.
FERRUCCIO TRINCHERO.
